CLAIM

The ornamental design for a microscope housing, as shown and described.

DESCRIPTION

FIG. 1 is a front perspective view of a microscope housing showing our new design with the monitor in a vertical state; FIG. 2 is a front view thereof; FIG. 3 is a rear view thereof; FIG. 4 is a right side view thereof; FIG. 5 is a left side view thereof; FIG. 6 is a top view thereof; FIG. 7 is a bottom view thereof; FIG. 8 is a front perspective view of the microscope housing of FIG. 1, showing the monitor in a horizontal state; FIG. 9 is a front perspective view of the microscope housing of FIG. 1, showing the monitor in a vertical state; the top three layers of the unclaimed platform are moved to the side; FIG. 10 is a front perspective view thereof with the top layer of the platform positioned to the front; and, FIG. 11 is a front perspective view thereof with the top three layers of the platform moved to the side and the very top layer of the platform positioned in the front. The broken lines in the drawings depict portions of the microscope housing that form no part of the claimed design.
